UNITED STATES PATENT OFFICE.

JAMES M. CARNAHAN, OF BELLS CAMP, PENNSYLVANIA.

LAMP.

SPECIFICATION forming part of Letters Patent No. 241,298, dated May 10, 1881.

Application filed March 10, 1881. (No model.)

To all whom it may concern:

Be it known that I, JAMES M. CARNAHAN, a citizen of the United States, resident at Bells Camp, in the county of McKean and State of Pennsylvania, have invented certain new and useful Improvements in Lamps; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 is a representation of a vertical section, and Figs. 2 and 3 are detail views.

This invention relates to lamp attachments; and it consists of a chamber connected with the oil-receptacle, and having a circuitous passage, an overflow, an exit for the gas, and a non-inflammable fluid in the chamber, through which the gas escapes, as will be hereinafter fully described, and particularly pointed out in the claim.

In the annexed drawings, A is the reservoir, made round or flat. Projecting from the bottom upward is a diaphragm, a, leaving a space, b, at the top, and from the top downward another, c, leaving a space, d, at the bottom. These diaphragms divide the reservoir into two chambers, B and C, and a connecting passage, D.

E is a tube leading into the top of chamber B, screw-threaded at e, tapered at e', and having the passage E'.

F is a hole made in the side of this chamber B, for use as an overflow or exit for the

non-inflammable liquid both in filling the chambers and during the passage of the gas, which escapes through the non-inflammable material whenever gas is generated in the reservoir. Some non-inflammable fluid is to be poured into chamber B until it is on a level with hole F, as indicated by the dotted lines.

The reservoir thus described can be connected to the lamp in several ways. As shown in Fig. 2, its base may be screw-threaded, as at e², and it may be inserted into the filling-hole of the lamp, having communication therewith by the tube f, leading from the bottom of chamber C; or it may be connected by a neck, g, to the collar G of the lamp, communication being had through the neck, which is hollow to the bottom.

As a still further modification, chamber C may be dispensed with and the reservoir connected to the collar at the top, the tube running from space b, and thus leading into the top of passage D.

I claim—

As an improvement in lamp attachments, a chamber connected with the oil-receptacle and having a circuitous passage, an overflow, an exit for the gas, and a non-inflammable fluid in the chamber through which the gas escapes, substantially as and for the purposes set forth.

In testimony whereof I affix my signature in presence of two witnesses.

J. M. CARNAHAN.
